US0D1031803S

(12) **United States Design Patent** (10) **Patent No.:** **US D1,031,803 S**
(45) **Date of Patent:** **** Jun. 18, 2024**

(54) **LAMINATING MACHINE**

(71) Applicant: **Foshan Lanbi Technology Co., Ltd.**,
Foshan (CN)

(72) Inventor: **HaiJiao Qu**, Foshan (CN)

(73) Assignee: **FOSHAN LANBI TECHNOLOGY CO., LTD.**, Foshan (CN)

(**) Term: **15 Years**

(21) Appl. No.: **29/791,082**

(22) Filed: **Dec. 29, 2021**

(51) **LOC (14) Cl.** **08-05**

(52) **U.S. Cl.**

USPC **D8/14**; D8/354; D14/432; D14/440

(58) **Field of Classification Search**

USPC D15/134, 146; D18/50, 55; D14/125,

D14/214-216, 422, 432, 440; D8/14, 354

(57) **CLAIM**

The ornamental design for a laminating machine, as shown and described.

DESCRIPTION

FIG. 1 is a first perspective view of a laminating machine showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.
